UNITED STATES PATENT OFFICE.

WALTER SCOTT, OF PLAINFIELD, NEW JERSEY.

PRINTING-MACHINE.

SPECIFICATION forming part of Letters Patent No. 317,679, dated May 12, 1885.

Application filed January 29, 1884. (No model.)

To all whom it may concern:

Be it known that I, WALTER SCOTT, of Plainfield, in the county of Union and State of New Jersey, have invented an Improvement 5 in Printing-Machines, of which the following is a specification.

In this press I make use of two rolls of paper; the webs are drawn off from the same and passed together between cylinders that measure 10 the length of sheet and partially separate the same by rows of perforations; the sheets are then conveyed by belts to impression-cylinders above and below the revolving type-cylinder, the motion being accelerated so as to 15 separate the sheets at the perforations; the sheets are taken by a second set of impression-cylinders and thereby reversed and their unprinted surfaces brought into contact with the types upon a second printing-cylinder. From 20 thence the sheets are conveyed away to any suitable delivery apparatus, or to folding-machines. By this improvement both sides of the sheets from two webs are printed before delivery from the press.

25 In the drawings, Figure 1 is a longitudinal section of the press. Fig. 2 is a diagram representing the frame and the manner in which the parts can be geared; and Fig. 3 shows one of the ends of a roll of paper and its friction- 30 brake.

The cylinders A and A' are provided with form-sections a and a', and with ink-distributing surfaces b and b', and they are revolved in opposite directions, as indicated by the arrows. 35 The printing-sections occupy not more than one-half of the periphery of each form-cylinder. The impression-cylinders B and B' are half the diameter of the form-cylinders, and they are provided with grippers b² and b³, and 40 are rotated in the directions indicated by the arrows. The sheets are brought to these impression-cylinders by the tapes or belts e e' around the respective rollers f, f', f², f³, f⁴, f⁶, and e⁵, and the sheet is drawn apart by the 45 accelerated movement given to it when the advancing end reaches the roller e⁵, and it is gripped thereupon by the tapes e', and the sheet is taken by the grippers b² of the impression-cylinder B, carried beneath the same up and 50 into contact with the printing surface or section a of the form-cylinder A'; then it is carried around by the cylinder B until it reaches

the impression-cylinder B', where the grippers b² release the same, and the grippers b³ take the sheet and carry it up, and it receives the second 55 impression on the other side from the printing-section a' of the cylinder A', and the sheet is carried off by the belts or tapes e e', that pass around B', 16, 15, 14, and 13 to a folding-machine or other delivering device. These parts 60 thus far described are similar to those in my Patent No. 312,022, and hence do not require further description herein, and they are not separately claimed.

The ink-troughs H H, the distributing-cylinders G G, the working and inking rollers g g, and the doctors h h' h' are arranged as shown, and supply ink from the respective troughs to the tables b b' on the respective cylinders A A'. The inking-rollers S S and the frames 70 carrying the same are moved in and out by cams, as in my aforesaid application. These rollers, however, for convenience, are placed in the positions shown to give more space for the other parts that are combined in this press. The doctor-roller h is received by arms that extend out from the rock-shaft h⁶, and are provided with slotted bearings at their ends, and the doctor-roller h' is upon arms that also extend out from the same shaft h⁶, and to the 80 rock-shaft the proper motion is given by a cam upon the shaft n or other suitable mechanism. By this construction the doctor-rollers h h' are moved simultaneously, the roller h transferring ink from the trough to the distributing- 85 cylinder G, and the roller h' transfers ink from G to the surface b of the cylinder A. The parts are duplicated for the cylinder A'. The ink is supplied by the doctor h to the cylinder G, while the doctor h' is not in contact therewith; 90 hence the fresh ink on G is distributed before the doctor h' is brought back into contact with it. This insures more perfect distribution of the ink.

Instead of using one roll of paper, I make 95 use of the two rolls F F². The shafts F³ F⁴ of the same are received into the bearings 21 22, the upper parts of which are by preference hinged so as to facilitate opening and closing, and provided with a thumb-nut or turn-button for 100 holding the parts in place when closed upon the shaft. Each roll is provided with a brake-bar, v', the ends of which are received in and guided by the slotted frames F⁵, and beneath

each end of such brake-bars there is a spring, v , and a guide-rod for the same. The springs raise the brake-bars v' and apply sufficient friction to the surfaces of the rolls of paper to prevent such rolls revolving too rapidly when the press is in operation. The two sheets or webs of paper are taken off from the rolls between the two pairs of cylinders E E' and D D'. These cylinders are of different diameters in cases where it is desired to use sheets of different lengths in the press. Each cylinder D and E' is adapted to receive the knife d , with a row of penetrating points, to partially cut the web off into sheets, and each cylinder E D' is grooved so that the points of the knife may enter into the same. If the knife is placed in the cylinder E', the length of sheet cut off will be greater than when the knife is placed in D. The cutting cylinders are to be revolved once for each revolution of the form-cylinders, and the pair of cylinders that is not provided with the knife may be slightly separated, so as only to guide the paper passing through between them, and thus allow the paper to be drawn and measured by the other pair of cylinders; or it will usually be preferable to maintain the same surface-speed in all four rollers, D D' E E', by the gearing 25 26 27 28 29, (represented by dotted lines in Fig. 2,) and to provide bevel-gears 30 31 and 32 33 to give motion from the driving-shaft n to either the cutting-cylinder D or the cutting-cylinder E', the gear that is upon the shaft of the cutting-cylinder that is not provided with the cutter being either removed or loosened, so as to turn independently of the shaft and allow the motion to be given to the other cutting-cylinder, and from it to the four cylinders, at a uniform surface-speed, and with one revolution for each revolution of the printing-cylinder A. The impression-cylinders T and T' are above the form-cylinders A A' and supported in adjustable journal-bearings in the frames A³. These cylinders T T' are provided with grippers t' and t^2 , and as the cylinders revolve twice for each revolution of the form-cylinders and the grippers t' , after taking the sheet, do not deliver the same to the grippers t^2 until the second revolution of T, it is necessary to employ the cams 40 50 upon the lever or rocker J³, similar to the rocker J and cams 4 and 5, that are employed in connection with the impression-cylinders B and B', and these rockers J J³ are to be moved by eccentrics or cams upon the shafts of the form-cylinder, as set forth in my aforesaid application, or in any other convenient manner. The tapes l l', that convey the sheets of paper and separate the same successively from the web, are passed around the respective rollers l² l³ l⁴ l⁵ l⁶ l⁷ l⁸, and act in the same manner as the tapes e e'; but it is necessary to throw back these belts l l' sufficiently to give access to the form-cylinder A for introducing the types, stereotypes, or other printing-surfaces, or for withdrawing or removing the same. I therefore provide arms p , that receive at their outer ends the

journals of the rollers l⁴ l⁵, and these arms p are either pivoted to the frames A³ or to the shaft of the roller l⁷; hence, when the arms p are swung up, they carry with them the rollers l⁴ l⁵ and tapes; the latter are loosened and the parts are removed out of way to give access to the cylinder A.

By reference to Fig. 1 it will be understood that the sheet passing up to the impression-cylinder T by the belts l l' is separated by the belts at l¹ and accelerated, and the advancing end of the sheet is seized by the grippers t' and carried down to the point of impression upon the surface a much sooner than the sheet that is carried to the cylinder B by the belts e e', because such sheet has to be carried from the under to the upper side of such cylinder B before it reaches the printing-surface a; hence the advancing end of the printing-surface a reaches the impression-cylinder B at the right time to print the sheet as it is presented by the said cylinder B.

Although the printing-surface a is first in contact with the sheet on the impression-cylinder T, the sheet on the impression-cylinder B will not be in position to be printed until the advancing edge of the printing-surface a reaches said cylinder B. The sheet after it has been printed on the cylinder T is carried around by the grippers t' until the grippers t² of the cylinder T' receive the same and the grippers t' are opened by the cam 40. The cylinder T' carries the sheet up and brings it down to the cylinder A' by the time the printing-surface a' reaches said cylinder T'. The second impression is then made and the grippers t² retain their hold, the cam 50 being out of the way as the grippers pass the same, and then the grippers t² are opened by the cam 41 at the same time that the grippers t³ are closed by the cam 51, and the sheet is taken upon the delivery-cylinder T² and carried around and delivered between the belts m m', and by them conveyed to any suitable folding or other delivering apparatus. The belts or tapes m pass around the cylinder T² and roller n², and the belts m' pass around the rollers n' n⁴. The grippers t³ retain their hold upon the sheet until its advancing end passes in between the roller n⁴ and the cylinder T², and the said gripper t³ is opened at this point by a stationary cam. The lever J⁴ is moved by an eccentric or cam upon the shaft b⁶ so as to swing the cams 41 51 into the path of the gripper wrists or cranks at the proper time for opening or closing the same. The levers J J³ J⁴ are all similarly actuated so that their cams are made to act in the desired manner upon the respective grippers. The shafts 10 and 11 of the impression-cylinders T T' are to be in adjustable bearings in the frame, so that the impression may be adjusted, and the shaft 12 of the delivery-cylinder T² is placed in the side lever-arms n³; so also is the shaft of the roller n², and these side lever-arms n³ have the shaft 11 as their pivot, so that the levers can be swung up and carry the delivery-

cylinder T^2 , belts m , and roller n^2 up out of the way to give access to the printing-surface a' of the cylinder A' , and the roller n^1 may be lifted out of its jaws 42 in the frame A^3 to get 5 the same and the belts m' out of the way. When the press is in use, the shaft 12 is received in jaws 43. If the cylinder T^2 is placed in the position indicated by the dotted lines, Fig. 1, it will be sufficiently high to allow access 10 beneath it to the printing-surface a' , and hence said cylinder T^2 may be stationary. It is usually preferable to allow the grippers t' to remain open after having delivered the sheet to the grippers t' until they come around 15 the second time and close upon the sheet as its advancing end is presented by the belts $l l'$. In this case the cam 44 may be placed upon a lever, 45, and be moved by a cam or eccentric on a^6 to bring it into and out of the 20 path of the crank or wrist of the grippers t' .

Upon reference to the dotted circles in the diagram, Fig. 2, it will be apparent that the gear-wheels indicated by these dotted circles can be used for giving the proper motions to 25 the respective parts; but I do not limit myself to this manner of arranging the gearing.

It is to be understood that any sheet-seizing device—such as pins or a suction apparatus—may be used in place of the grippers, and, being 30 well-known, are the equivalents of the grippers.

This arrangement of impression-cylinders might be used with feed boards or tables to supply the sheets by hand to the cylinders B 35 and T , or such sheets may be supplied from one roll of paper with suitable switch and tapes to direct the sheets successively and alternately to the cylinders B and T . Devices that will supply sheets in this manner are well 40 known.

It is preferable to employ composition inking-rollers $s^2 s^3$ between the cylinders A A' to ink the printing-surfaces between one impression and the next. These rollers $s^2 s^3$ should 45 be placed upon frames and moved in and out, the same as the other rollers, s . The journals of the rollers e^5 and l^7 are in bearings that are movable, and screws and nuts are employed to retain the bearings in place. The object of 50 this adjustment is to allow for the introduction of longer or shorter tapes or belts, so as to accurately adjust the distance the sheets have to travel between the place where they are cut, and where they are received by the respective grippers, so that the impression may 55 be made upon the sheet with uniformity of margin.

I do not claim any portion of the inking apparatus separately, but when the form-cylinders are used with four impression-cylinders it is necessary to arrange the inking-rollers in such a manner that the types will be inked twice during each revolution of each form-cylinder. I have therefore combined the 60 inking-rollers with the said form-cylinders and impression-cylinders in the manner before

described to accomplish this object. In my Patent No. 312,022 two form-cylinders with ink-distributing surfaces are made use of in combination with two impression-cylinders, 70 the sheet being taken from one impression-cylinder and reversed and presented to the second type-cylinder. I do not in this application, therefore, lay claim to any such device.

I claim as my invention—

1. The combination, with two form-cylinders having printing-surfaces and ink-distributing surfaces, of four impression-cylinders and their respective grippers, substantially as set forth.

2. The combination, with two form-cylinders 80 having printing and ink-distributing surfaces, of four impression-cylinders and their respective grippers, belts for conveying the sheets of paper, the rollers for the respective belts, the cutting-cylinders, and feeding mechanism, substantially as specified, for conveying to the respective impression-cylinders sheets cut from two rolls of paper, substantially as set forth.

3. In combination with a form-cylinder having printing and ink-distributing surfaces, 90 two pairs of cutting-cylinders of different diameters, and a knife that can be applied to either cylinder, whereby the web can be cut off in sheets of different lengths, substantially as set forth.

4. The combination, with the cylinders E E' D' and the cutter or knife, of the shaft n , bevel-gears 30 31, 32 33, for connecting the shaft of the cylinder D or of the cylinder E' to the shaft n , and the wheels 25 26 27, 28 29, 100 for connecting all the cylinders together, substantially as set forth.

5. The combination, with the two form-cylinders having printing and ink-distributing surfaces, of the impression-cylinders T T' 105 above the form-cylinders, the impression cylinders B B' below the form-cylinders, the ink-troughs and rollers, ink-distributing cylinders G , and rollers, the doctors h h' h'' , the rock-shafts and arms thereon for supporting and 110 moving the doctor-rollers simultaneously, the said parts occupying positions in two separate sets at opposite sides of the central portions of the form-cylinders G , the inking-rollers s s , and the inking-rollers $s^2 s^3$ between the form-cylinders to ink the respective printing surfaces between each impression, substantially 115 as set forth.

6. The combination of the cylinder A , impression-cylinders B T , tapes or belts e e' l l' , 120 and their respective rollers, and the arms p , substantially as and for the purposes set forth.

7. The combination, with the cylinder A' and impression-cylinder T' , of the delivery-cylinder T^2 , belts m m' , rollers n' n^4 n^2 , and arms 125 n^3 , substantially as set forth.

8. The combination, with the box and shaft for holding the paper-roll, of the brake v' , springs v , and guide-frame F^6 , substantially 130 as set forth.

9. The combination, with the form-cylinder, of two impression-cylinders, mechanism, sub-

stantially as specified, for cutting the web of paper from two rolls into sheets, and for conveying the same to the impression-cylinders, and an adjusting device for moving the roller 5 e^5 or l^7 , or both, and allowing the length of the belts to be varied, for the purposes and substantially as set forth.

Signed by me this 25th day of January, A. D. 1884.

WALTER SCOTT.
